[57] CLAIM

The ornamental design for an apparatus for metering and dispensing detergent, as shown and described.

DESCRIPTION

FIG. 1 is a top perspective view in an open position of an apparatus for metering and dispensing detergent showing our new design;

FIG. 2 is a perspective view thereof in a closed position;

FIG. 3 is a front elevational view thereof;

FIG. 4 is an enlarged left side elevational view thereof;

FIG. 5 is an enlarged right side elevational view thereof;

FIG. 6 is an enlarged top plan view thereof;

FIG. 7 is an enlarged bottom plan view thereof; and

FIG. 8 is an enlarged rear elevational view thereof.

FIG. 1**FIG. 2****FIG. 3**

FIG. 4
